UNITED STATES PATENT OFFICE.

LEON ST. DENIS MALONE, OF ROCHESTER, PENNSYLVANIA, ASSIGNOR OF ONE-HALF TO
NANCY H. H. DE FORD, OF BALTIMORE, MARYLAND, AND ONE-HALF TO ELIZABETH
H. FINNEY, OF EVANSTON, ILLINOIS.

DESIGN FOR A TOY ANIMAL.

54,940.

Specification for Design.

Patented Apr. 20, 1920.

Application filed May 20, 1919. Serial No. 298,568. Term of patent 3½ years.

To all whom it may concern:

Be it known that I, LEON ST. DENIS MALONE, a citizen of the United States of America, and resident of the city of Rochester, State of Pennsylvania, have invented a certain new, original, and ornamental Design for a Toy Animal, of which the following is a specification, reference being had to the accompanying drawing, forming part thereof.

The figure is an elevation of a toy animal, showing my new design.

I claim:

The ornamental design for a toy animal as shown.

Signed by me at Baltimore, Maryland, this 19th day of May, 1919.

LEON ST. DENIS MALONE.

Witnesses:

E. AHLSLEGER,
PORTER H. FLAUTT.
